UNITED STATES PATENT OFFICE.

GEORGES ROESCH, OF LONDON, ENGLAND, ASSIGNOR OF ONE-HALF TO CLEMENT TALBOT LIMITED, OF LONDON, ENGLAND.

DESIGN FOR A COMBINED MUD-GUARD AND LUGGAGE-CARRIER.

52,709.

Specification for Design.

Patented Nov. 19, 1918.

Application filed November 23, 1917. Serial No. 203,634. Term of patent 14 years.

To all whom it may concern:

Be it known that I, GEORGES ROESCH, a citizen of the Swiss Confederation, residing at Barlby Road, Ladbroke Grove, London, England, have invented a new, original, and ornamental Design for Combined Mud-Guard and Luggage-Carrier for an Automobile, of which the following is a specification, reference being had to the accompanying drawing, forming part thereof.

Figure 1 is a perspective view from the side illustrating my ornamental design for

combined mud guards and luggage carrier for automobiles.

Fig. 2 is a plan view thereof.

I claim:

The ornamental design for combined mud guard and luggage carrier for an automobile, as shown.

GEORGES ROESCH.
